UNITED STATES PATENT OFFICE.

EMIL JACOBSEN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed May 20, 1918. Serial No. 235,436.

To all whom it may concern:

Be it known that I, EMIL JACOBSEN, a citizen of the United States of America, and a resident of Chicago, in the county of Cook 5 and State of Illinois, have invented certain new and useful Improvements in Automatic Telephone Systems, of which the following is a specification.

My invention relates in general to a telephone system in which connections are established between subscribers by means of 10 automatic switches without the intervention of an operator.

Among the objects of my invention are 15 to provide means for increasing the capacity of such an exchange system without material addition of apparatus, cut down the operations required of a subscriber in locating a desired called subscriber's line, provide new 20 methods of operation to call a subscriber, provide improved switches to be operated by the subscribers and to generally improve the efficiency of such a system and increase its flexibility.

25 In the automatic telephone systems which have been installed prior to this time, one of the greatest objections to its acceptance by the public has been the large number of figures which it is necessary to remember 30 when calling another subscriber by means of an automatic calling device. For instance in a large exchange it is often necessary to send as many as 7 or 8 figures to the switches of the exchange before the called line is 35 reached, and the calling device must be operated a like number of times. In case a number of private branch exchanges are connected to the system, then a still greater number of digits is required and it will be 40 seen that should automatic long distance operation be desired between large cities the number of digits would become very large and hard to remember.

45 The reason for so many digits being required is that it has been determined that a system operates most efficiently when the switches have access to 100 trunks or lines only, that is, 10 groups of ten levels of contacts and although the switches might simply be increased by making each switch have 50 access to more trunks or lines, yet, if this were done, the time of operation of the switch would be too long and the digits or directory numbers would be confusing.

In order to accomplish the desired results 55 and provide a system which is free from such difficulties, I have provided automatic selector switches each having access to twice the number of trunk lines (or 200 trunks) and connector switches having access to four 60 times the usual number (or 400) subscribers' lines. To further aid in producing the desired results I have so arranged these large capacity switches that only the regular number of steps (10) both vertical and rotary 65 are required and have provided a calling device which although very similar to that now employed in standard systems, is especially adapted to control the said large capacity switches. 70

Having given a general outline of the features and objects of my invention I will describe the particular embodiment of my invention as shown in the drawings.

Figure 1 shows a calling subscriber's line 75 A having a line switch C of the well known rotary type individual thereto and being of the usual common battery type of substation having a receiver 2, transmitter 3, calling device CD, switch hook 4 and its controlling 80 springs, and a resistance 5 in series with the line circuit which is adapted to be cut out of the line circuit by the operation of the springs 6 and 7 which are controlled by the calling device in a manner to be explained. 85

The line switch C has access to a plurality of selectors D, which are of the well known Keith Erickson type having vertical motion to elect a group of trunks and rotary motion to select an idle trunk in the group, except that the circuits have been changed somewhat to adapt it to operate in accordance with the principles of my invention. The selector is provided with two line banks and two private banks one above the other 90 and has a pair of line wipers and a pair of private wipers cooperating with each line and private bank. Before the switch is operated a relay is controlled which cuts out one or the other of said pairs of wipers so that a trunk line will be selected in either the lower or upper banks, depending upon which set of wipers has been made effective.

100 The selector switch D has access to a number of trunk lines in both its upper and lower banks (100 in each bank) so that the trunk lines in the lower level may all lead to repeaters such as E and through said re-

peaters to connectors such as H (Fig. 2). The trunks in the upper level which cooperate with the upper set of wipers may be for local calls only or the trunks in each bank 5 may lead to different groups of switches.

The repeaters E are of a well known type of repeater which simply receives impulses from a substation and repeats them to the trunk line to which they are connected except that certain circuit changes have been 10 made to adapt them to a system embodying my invention.

Associated with each trunk line from a repeater E are connector switches H (Fig. 15) 2) although it will be understood that selector switches similar to that shown at D may be inserted between the repeaters and connectors. The connector H is of the standard Keith Erickson type of connector except that it is provided with 4 sets of wipers, 20 four line banks and four private banks, and is also provided with certain novel means for switching the trunk line to any desired set of wipers.

25 In Figures 3 and 4 I have shown two alternative methods by means of which my invention may be employed. In these figures I have shown only the substations with the arrangement of the circuit thereat and the 30 manner of arranging the controlling relays of a switch to cooperate therewith.

Figure 5 shows a front view of the calling device used in my improved system showing the arrangement of the finger holes 35 and the spring contacts controlled thereby.

Having given the general objects of my invention, I will point out in detail the operation of the system, reference being had to the accompanying drawings.

40 The calling device used in this system is arranged (as shown in Figure 5) with two rows of finger holes. The numbers in each set of holes being alike except that the inside row of figures from 1 to 0 are printed in red while the outside row are printed in black. A pair of make springs are mounted as shown underneath the front plate of the calling device and directly in the path of the finger holes of the outer or black 45 number finger holes. Now if a subscriber inserts a finger in one of the said outside holes and rotates the same around till his finger meets the finger stop, then as the finger meets the said springs, they will be 50 closed into contact. The holes are so arranged that if either the red or black numbers are used only ten impulses may be sent. That is if the subscriber inserts a finger in the number three (red) hole and operates 55 the device three impulses will be delivered in the usual manner as is well known to those versed in the art. If the subscriber operates the device by using the number three (black) hole then three impulses will also 60 be sent in the usual manner, except that in

addition to the three impulses, a circuit will be closed by the springs 6 and 7 as shown at substation A (Fig. 1).

Now when the subscriber at A removes his receiver to initiate a call, a circuit will be 70 closed by the switch hook springs for the line relay 8 of the line switch C in the usual manner, which relay in turn closes a series circuit at springs 9 for switching relay 10 and rotary magnet 11. If the trunk line on 75 which the switch C is resting is busy then ground from the private wiper 14 will maintain the relay 10 short circuited and will cause the magnet 11 to operate intermittently to rotate the wipers to an idle trunk line, 80 at which time, the short circuiting of relay 10 being discontinued, said relay energizes over the series circuit to disconnect the relay 8 and ground from the line and to connect the line of substation A through its 85 contacts to the wipers 12 and 13 and thence to the trunk line leading to the idle selector D. Relay 10 being of a relatively high resistance does not permit the magnet 11 to energize in the above traced series circuit. 90

As soon as relay 10 energizes a circuit is closed for the line relay 15 of the selector D in series with the line of substation A and the marginal relay 26 which does not energize in series with the high resistance 95 5 at the substation. It will be seen that the subscriber, instead of having to send 2 digits to first pick out one of a hundred trunks by the selector D, and then having to operate another selector to pick out one of another 100 hundred trunks has access to two hundred trunks directly from the selector D, there being two banks of 100 lines each. If the subscriber desires to call a subscriber in one group or division of the exchange, he 105 will first choose one of the two banks by determining which wiper he will use. That is the wiper he will use and therefore the bank over which his call will be extended depends upon which row of finger holes on the dial 110 he uses to call the first digit (red or black).

Therefore assuming that the number of the subscriber he desires to call appears in the directory as 2 (red) 4 (red) 5 (red) then the subscriber will insert a finger in the inside hole marked 2 (red) and operate the calling device in the usual manner to separate the springs CD at the substation, two times. The relay 15 in response to this series of impulses operates to control the vertical magnet 16 and series relay 17 through contacts of slow relay 18 (which is maintained energized) to operate said magnet to step the wipers 20—25 inclusive, up to the second level of their banks. As the switching relay 19 and marginal relay 26 are deenergized at this time, only the lower set of line and private wipers are effective, being connected to the line circuit through back contacts of relay 19, while wipers 20, 21 and 22 120 125 130

are open. As soon as the switch steps off normal and springs 27 close, a circuit is closed by relays 18 and 17 through relay 28 to prepare the circuit of rotary magnet 29. 5 Now when relay 17 falls back after this digit, a circuit is closed for the rotary magnet 29 through the front contact of relay 18, the back contact of relay 17 and the front contact of relay 28. The magnet 29 operates to 10 step the wipers 20 to 25 onto the first contacts of their respective banks and to open the circuit of relay 28 at springs 30. As only the private wiper 25 is effective the wipers will be rotated until an idle trunk line in the 15 lower bank is reached without regard to the condition of the trunks in the upper bank. Ground from busy trunks controls relay 28 to perform this trunk selecting operation. When an idle trunk is reached, the relay 31, 20 which has been short circuited by the ground on the private wiper while passing over busy trunks, energizes in series with relay 28 from ground on springs of relay 18. Relay 31 being of comparatively high resistance does not permit the energization of the 25 relay 28 at this time. Relay 31 upon energizing, disconnects the magnets of the selector D from the line of substation A and connects said line through to the wipers 23 and 24 which it will be assumed have selected 30 and come to rest upon the contacts of the lower bank to which the trunk line leading to connector H through the repeater E is connected. As soon as relay 31 energizes the 35 circuit of the line relay 32 of the repeater E is closed, as was the line relay 15 of selector D, in series with the calling line and marginal relay 33. Relay 33 (like relay 26) does not energize in series with the high 40 resistance 5 at the substation.

The next digit being 4 (red), the subscriber will again operate the dial this time to send four impulses to the relay 32. Springs 6 and 7 are not operated and the operation of the repeater line relay is as usual, 45 that is, relay 32 by the operation of springs 34 repeats the four impulses of this digit to the line relay 35 of the connector H over a circuit including the resistance 36, which is 50 of the same resistance as that shown at 5 at the substation. The circuit of the line relay 35 of the connector extends from ground through the lower winding of said relay, springs 37, off normal springs 38, resistance 55 36, springs 34, upper winding of switching relay 39, springs 40, and upper winding of the line relay to battery. The relay 39 which is included in this circuit is a marginal relay similar to relays 33 and 26 and does not energize in series with resistance 36. As this 60 circuit is now interrupted four times in accordance with this digit, the line relay 35 falls back to step the wipers 41-52, four steps to the fourth level of their banks by 65 means of the vertical magnet 53, which is en-

ergized in the usual manner over a circuit including the back contacts of relay 35, front contacts of relay 54, (which is held energized) springs 55, and relay 56 and magnet 53 in series to battery. As soon as 70 relay 56 energizes and the switch takes one step, the springs 38 are opened and springs 58 are closed, springs 55 are opened and springs 57 are closed, so that the vertical magnet circuit will now pass through the 75 springs 57 and front contacts of relay 56 which remains energized during impulses of this digit. The next digit of the called number being 5 (red) the subscriber will again 80 operate his calling device to send five impulses without shorting resistance 5 at the phone and therefore without shorting the resistance 36 at the repeater. The line relay 35 will now respond to the impulses of this digit to operate the rotary magnet 59 over a 85 circuit from ground through back contacts of relay 56, springs 60, relay 61, and magnet 59 to battery. Magnet 59 is operated to step all the wipers 41-52 to the fifth contact of their respective banks. As relays 39 and 62 90 are in normal position, only the wipers 41, 42 and 43 are effective, the other wipers being open at one or the other of said relays. Therefore although the switch H has stepped its wipers in such a manner that 95 each set has connected with a different subscriber's line, one at line 63-65, one at line 66-68, one at 69-71 and another at 72-74, still a connection will be extended to only one of said lines, namely, line 72-74. The 100 subscriber has therefore picked out one of 400 lines by operating a switch by only two digits, each having less than 10 impulses. The relay 61 which energized in series with the rotary magnet, remains energized during the impulses of this digit and for a second thereafter to hold the private wiper 43 connected to the busy test relay 75. If 105 this line is busy, relay 75 will operate in the usual manner to connect a busy tone to the calling subscriber, open the circuit of wiper cut on relay 76, and open the circuit of rotary magnet at springs 60. If the called line is not busy then relay 75 will not energize and as soon as relay 61 falls back a 110 circuit will be closed for the relay 76 from ground through springs 77, springs 79, upper winding of relay 76, springs 78, and through the private wiper 43 to battery 115 through the bridge cut off relay of the called man's line switch. Relay 76 will therefore energize to open the circuit of the rotary magnet, close a locking circuit for its own lower winding, and connect ground direct to wiper 43 to hold the line busy. Relay 76 120 also closes the springs 80 and 81 to close a ringing circuit for the called line which extends from battery through the upper winding of the ring cut-off relay 82, springs 83, springs 80, wiper 41, called line ringer, wiper 125 130

42, springs 81, springs 84, and to ringing interrupter equipment R. As soon as the called subscriber answers relay 82 will energize to disconnect the interrupter R and connect the lines through for conversation, which may now be carried on over the heavy conductors which are shown leading through the lower wipers of each switch. The back bridge relay 85 energizes after relay 82 in series with the called line and operates to reverse the battery to the calling line for any purpose.

Now suppose another subscriber's line is to be called whose line is located in the second bank of the connector. If this line is located on the terminal in the second bank which corresponds to the terminal of the previously called subscriber in the lower bank then this subscriber's number will be 2 (red) 4 (red) 5 (black). The operations in calling this number will be exactly the same as just described in calling 2 (red) 4 (red) 5 (red) and the connection will be extended to the connector H and the connector H operated both vertical and rotary the same as before except that the last digit (5) will in this instance be dialed on the outside row of figures on the dial. When the number 5 is called on the black or outside row the springs 6 and 7 are momentarily closed by the finger of the subscriber (or in any other manner) just before the dial is allowed to return to send the five impulses.

The closure of the springs 6 and 7 short circuits the high resistance 5 at the telephone and causes the marginal relay 33 of the repeater E to energize. Relay 33, upon energizing, in turn short circuits the high resistance 36 in the circuit of the relays 35, 39 and 62 of the connector. The connector having been previously raised from normal the springs 38 are now opened and the circuit of the line relay 35 includes the upper winding of relay 39 and also the lower winding of relay 62. Relays 62 and 39 are both marginal, that is relay 62 will operate when the resistance 36 is shorted but relay 39 will not operate unless both the resistance 36 and the winding of relay 62 are shorted. In this instance then relay 62 will energize and will lock itself to ground through springs 77 and springs 86 and will also disconnect the normal wipers 41, 42 and 43 from the line circuit and connect the line circuit instead to the wipers 44, 45 and 46. Now therefore although all the wipers are rotated to the fifth contact of this level, only the wipers 44, 45 and 46 will be effective and the connection will be extended to the substation connected to line 69—71 in the second bank instead of to the line in the lower bank. The operations of the switches in each case being exactly similar.

Assume now that the subscriber desires to call a partly located on line 66—68 whose

line is located in the third bank of connector H. The operation will again be exactly similar except that the subscriber's number in this case would be 2 (red) 4 (black) 5 (red). The selector switch will again be operated in the same manner by this digit 2 (red) to seize the repeater E. Now when the second digit is called on the black dial the resistance 5 is shorted to pull up the relay 33 to in turn short the resistance 36. As the connector has not yet been raised from normal the springs 38 are closed and therefore only the relay 39 is now in the series circuit with the line relay. Now when resistance 36 is shorted, relay 39 will energize, lock itself to ground through springs 77 and 87 and will switch the line circuit from the normal wipers 41, 42 and 43 to the wipers 47, 48 and 49 through its own front contacts and the back contacts of relay 62. The last digit to the connector operates it in exactly the same manner as in the call first described to rotate the wipers to the fifth contact in the fourth level except that, relay 39, being energized the connection will be extended to the line 66—68 instead of 72—74. The testing operations are alike in all cases except that they are performed over different wipers and a different contact is tested in each case according to the wiper made effective.

Assume now that the subscriber desires to call the line 63—65 which is located in the fourth or top bank of the connector switch H. In this case the digit called would be 2 (red) 4 (black) 5 (black). The selector D will be again operated to seize the repeater E by the digit 2 (red). The repeater E will again operate as in the last described call to control the connector H to step it up four steps and to lock the relay 39 energized, thereby connecting the wipers 47, 48 and 49 to the line circuit. In this case, however, when the last digit 5 (black) is sent, the repeater E again operates to control the connector to step around to the fifth contact and at the same time, by shorting resistance 36, pulls up the relay 62 as in the case of the second call described. The relays 39 and 62 will both be locked energized in this call and therefore the line circuit will be switched through the front contacts of both of said relays to the wipers 50, 51 and 52. The wiper 52 is the only test wiper effective therefore and the connection will be extended to the line 63—65 over the line wipers 50 and 51. The release of the connection is exactly the same in each connection, the locking circuits of the relays 39 and 62 being opened by the deenergization of the slow relay 54.

I have now described how a call may be extended through the lower bank of the selector D to any of the lines accessible to connectors H which are accessible from said

lower bank. The upper bank of the selector D may lead to an exactly similar set of trunks as are connected to the lower bank, or said upper bank of the selector may be 5 connected to long distance trunk lines to another city, or to connectors, similar to H, directly for local calls. In fact the system may be divided up in any desired manner without departing from the spirit of my invention which relates mainly to the method 10 of controlling any desired series of switches. Assuming that the upper bank of the selector D leads to connector switches similar to H and that the calling subscriber desires to 15 call some other subscriber whose line is located in the lower bank of the connector switch. Now the called subscriber's number would be 2 (black) 4 (red) 5 (red). In this case the first digit will be called on the outside 20 or black row of figures on the dial, and as the dial is rotated by the subscriber, after the line switch has seized the selector, the springs 6 and 7 short the resistance 5 and cause the marginal relay 26 to pull up for an 25 instant to close a circuit at springs 88 for the switching relay 19. Relay 19 energizes to lock itself to ground at the springs of the release relay 18 and also connects the line circuit to the wipers 20, 21 and 22 instead of 30 to the wipers 23, 24 and 25. The selector will be operated in exactly the same manner as before pointed out except that, the wiper 25 being open, the switch will test trunks in the second level of the upper bank instead 35 of testing the trunks in the second level of the lower bank, and will connect with some trunk such as B which leads to a connector or another selector. The last two digits 4 (red) 5 (red) will be sent by the inner figures 40 on the dial and will operate the connector switch to extend the call over the fifth contact of the fourth level of the lower bank of such connector. I have shown therefore that a subscriber after seizing the selector D 45 may operate it by one digit of ten or less impulses to pick out an idle trunk in either of two large groups of trunk lines, the group being determined by the row of figures on the dial used, and that after extending the 50 call to the desired group of trunks he may operate a connector switch by means of two digits of ten or less impulses each to pick out any lines in four large groups of 100 lines each, the group again being determined 55 by the row of figures on the dial used. It will be understood that the trunking in this case may be more than ten percent, that is, more than ten connectors may be assigned to one group of 100 lines and each level of the 60 selectors may have 20 or 25 trunks as desired.

In Figures 3 and 4 I have shown alternate methods of arranging the substation circuit and the switching relays of the wipers. Referring to Fig. 3, instead of having

the springs 6 and 7 short a high resistance I have shown a pair of springs 6' and 7' for grounding one side of the line to pull up a differential relay 26' which will perform the same functions as the relay 26 (Fig. 1). 70 In Fig. 4, I have shown the springs 6'' and 7'' which operate the same as springs 6 and 7 (Fig. 1) except that they include a high resistance in the line circuit instead of shorting a high resistance, to cause a marginal relay 26'' to operate to control the switching over of the wipers. It will be understood that these alternative methods might be applied to the switches D, E and H without any important changes in the circuits as 75 shown.

Having fully described and ascertained my invention what I consider to be new and desire to have protected by Letters Patent will be pointed out in the appended claims. 80

What I claim as my invention is:

1. In a telephone system, a calling line, an automatic switch associated with said line having a pair of wipers, an element for moving said wipers, a calling device associated with the line for controlling said switch, and means in the switch for automatically rendering an alternate one of said wipers effective after the element has been moved in response to the first digit and before the digit. 90

2. In a telephone system, a calling line, an automatic switch associated with said line, other lines accessible to said switch divided into groups, a device associated with said calling line for operating the switch to extend connections from said calling line to said other lines, and means associated with said switch and automatically controlled after the switch is operated in response to the first digit and before the switch is operated in response to the second digit for predetermined the group into which the connection is to be extended. 100

3. In a telephone system, a calling line having an automatic switch associated therewith having access to a plurality of large groups of lines, each group being further divided into sub-groups, said switch having motion in one plane to elect one of said sub-groups and in another plane to select a line in the elected sub-groups, and means associated with the switch and automatically operated for electing a group of said lines, said group electing means operable either before the switch is moved or after it has moved in one plane. 110

4. In a telephone system, a calling line having an automatic switch associated therewith having access to a plurality of large groups of lines, each group being further divided into sub-groups, said switch having motion in one plane to elect one of said sub-groups and in another plane to select a line 125 130

in the elected sub-group, and means associated with the switch and automatically operated for electing a group of said lines, said group electing means operable in part 5 before the switch has moved in either plane and in part after the switch has moved in one plane.

5. In a telephone system, a line, an automatic switch for said line having a plurality 10 of series of wipers associated therewith, each series for extending connections into different groups of lines, a calling device for operating said switch to move said wipers into engagement with called lines, and means automatically controlled by said calling device 15 independent of the operation for moving the wipers, for limiting the call to one of said series of wipers before the switch is operated and for limiting the call to one wiper 20 in the elected series after the switch is operated.

6. In a telephone system, an automatic switch, a line leading thereto, a calling device for sending impulses of current to said 25 switch, a repeater interposed in said line operated by the calling device to repeat said impulses therefrom to said switch, means controlled by the calling device for transmitting 30 an impulse of increased strength to said repeater, said repeater responsive to said impulse of increased strength to transmit an impulse of increased strength to the automatic switch.

7. In a telephone system, an impulse repeater, an automatic switch, a calling device 35 for transmitting impulses of one character to said repeater, in accordance with a digit of a called number, means in the repeater for repeating said impulses to said automatic 40 switch to operate said switch, means associated with said calling device for transmitting an impulse of the same duration but of a different electrical character to said repeater over the same circuit preliminary to 45 the impulses of a digit, and means in the repeater for repeating said impulse of different character to the automatic switch.

8. In a telephone system, an impulse repeater, an automatic switch, a calling device 50 for transmitting impulses of different strength to said repeater, and means in the repeater responsive to weak impulses for transmitting weak impulses to the switch to perform one operation thereof and responsive to strong impulses to transmit 55 strong impulses to the switch to perform a different operation thereof.

9. In a telephone system, a trunk line having two inductively connected sections, a pair of relays in bridge of one section, a calling device for transmitting impulses of different character over one section of said trunk line, one of said relays responsive to impulses of one character to repeat impulses

of a corresponding character over the other section, and the other relay responsive to impulses of another character to repeat impulses of that character over the other section.

10. In a telephone system, an automatic 70 switch, a line leading thereto, a plurality of wiper sets therefor, a calling device on said line having mechanism for sending impulses to said switch to operate the same, auxiliary mechanism associated with the device for 75 sending impulses of a particular character to the switch at certain times to pick out one of said sets of wipers, and a repeater interposed in said line for receiving both characters of impulses and repeating them to said 80 automatic switch.

11. In a telephone system, a calling line, an automatic switch having two sets of wipers, means for extending said line to said switch, a resistance normally connected in series with 85 the line at the subscriber's station, a marginal relay included in the line at said switch for controlling the wiper selection, said relay being inoperative because of said resistance, and contacts in the subscriber's calling device 90 for short circuiting said resistance to operate said relay.

12. In a telephone system, an automatic switch having two sets of wipers, a calling device for controlling said switch having two 95 rows of finger holds, a line circuit over which the control is exercised, a resistance associated with said calling device and included in 100 said circuit, a normally inoperative relay included in said circuit at said switch, means controlled by said relay for switching from one set of wipers to the other, and contacts in said calling device for short circuiting said resistance to operate said relay whenever 105 said calling device is operated from a finger hold in a particular row.

13. In a telephone system, a selector and a connector for connecting a calling and called line, controlling circuits for said switches each including the two sides of the calling line in series, connecting mechanism in each switch requiring the associated control circuit to be first closed and then altered in two different ways in order to secure correct operation in establishing a connection, means at the station on the calling line for closing said circuits and for providing the required circuit alterations, a repeater interposed between said selector and connector, a trunk line between the repeater and the connector, and means in the repeater for repeating the alterations produced in the connector control circuit to said connector, over the two sides of 110 said trunk line in series.

Signed by me at Chicago, Cook County, 115 State of Illinois, this 10th day of April, 1918.

EMIL JACOBSEN.
